UNITED STATES PATENT OFFICE.

HERMAN G. WEILAGE, OF CRETE, NEBRASKA.

WASHING-MACHINE.

SPECIFICATION forming part of Letters Patent No. 597,344, dated January 11, 1898.

Application filed July 10, 1897. Serial No. 644,058. (No model.)

To all whom it may concern:

Be it known that I, HERMAN G. WEILAGE, of Crete, in the county of Saline and State of Nebraska, have invented a new and Improved 5 Washing-Machine, of which the following is a full, clear, and exact description.

The object of my invention is to provide a washing-machine by means of which clothes may be thoroughly cleaned without rubbing 10 them upon a board or together, thereby preventing the buttons from being broken off and fine fabrics from becoming damaged.

Another object of the invention is to so construct a washing-machine that air may be 15 compressed and brought into action to force the washing fluid through the clothes in a manner to thoroughly cleanse them, the compression of the air being effected in an exceedingly simple and expeditious manner.

Another object of the invention is to provide means for securing a compressing-table above a rocking grate at a distance from the grate necessitated by the number of pieces placed in the machine, which pieces are located between the compressing-table and the 25 rocking grate.

The invention consists in the novel construction and combination of the several parts, as will be hereinafter fully set forth, 30 and pointed out in the claims.

Reference is to be had to the accompanying drawings, forming a part of this specification, in which similar characters of reference indicate corresponding parts in all the figures.

Figure 1 is a plan view of the complete machine. Fig. 2 is a plan view of the machine, the compressing-table having been removed. Fig. 3 is a vertical section on the line 3 3 of Fig. 1. Fig. 4 is a bottom plan view of the compressing-table. Fig. 5 is a vertical section on the line 5 5 of Fig. 1. Fig. 6 is a detail inside view of a portion of the tank, tub, or body of the machine, partly in section, on the line 6 6 in Fig. 5, illustrating the locking device as applied to hold the compressing-table in position; and Fig. 7 is a view similar to Fig. 6, the locking device, however, being shown in a position which will enable the compressing-table to be removed from 45 the body of the washing-machine.

A represents a tub or tank, the tub or tank being represented as circular in the draw-

ings; but said tub or tank may be given any other contour, if desired. At opposite sides on the inner face of the tub or tank bifurcated standards B are secured by screws, rivets, or their equivalents, each of the standards comprising a member 10 and a member 11, connected by a base member 12, and in the upper central portion of the lower connecting member of each bracket a recess 13 is produced.

In the inner edge portion of the member 11 of each standard B a series of longitudinal recesses 14 is produced; but the standards are 65 so attached to the tub, tank, or body of the washing-machine that the plain member 10 of one standard will face the recessed member 11 of the opposing standard, as shown in Fig. 1.

A rocking grate C is located at the bottom of the tub, tank, or body of the machine, consisting of transverse bars 15, a main or central tie-bar 16, whose upper face is flush with the upper surfaces of the transverse or cross bars 15, and auxiliary tie-bars 17, which are simply let into the bottom portions of the transverse or cross bars 15. Trunnions 18 are formed at opposite ends of the grate, being at the end portions of the central tie-beam 16, and these 80 trunnions are made to enter the recesses 13 in the bottom portions of the bifurcated standards B. In this manner the grate may have a rocking movement on its supports. A compressing-table D is located above the 85 rocking grate. This compressing-table consists of a top 19, which is air-tight, a flange 20, extending downward from the margin of the top, a main central tie-beam 21, extending from flange to flange, and cross beams or 90 bars 22, extending from the sides of the tie-beam to the flange 20, as shown in Fig. 4. Preferably the compressing-table is flattened 95 opposite the ends of the tie-beam 21.

A trunnion 23 is formed at the center of 95 each flattened surface of the compressing-table, and upon each trunnion an arm 24 is pivoted, terminating in a latch-head 25, the arms being adapted to enter the spaces between the members of the bifurcated standards and the latch-heads being arranged to enter the recesses 14 in one of the members of the said standards, as shown in Figs. 6 and 7. A locking link or bar 26 is pivotally attached

to each latch-head 25, terminating at its free end in a head 27, which is in the nature of a bar and is adapted to engage with the inner edge of the straight members 10 of the bifurcated standards when the latch-heads have entered the recesses 14 in the opposing member of the standard. A handle 28 is secured to the top central portion of the compressing-table, being provided with suitable braces 29.

10 In operation the washing compound is placed in the tub, tank, or body A, and the clothes are placed upon the grate C. The compressing-table is then introduced into the tub, tank, or body, brought down to an engagement with the clothes, and secured by carrying the locking-links 26 to an engagement with the straight members of the standards. The compressing-table may now be rocked upon its pivot by means of the handle 28, and as each end of the compressing-table is carried or dipped downward it will compress the air, thereby causing the washing fluid to pass through the fabric of the articles being cleansed, the compressed air being more or less confined by the tie-beams in the grate C and the compressing-table. Thus it will be observed that alternately the washing compound will be forced through the clothes through the medium of the compressed air at opposite sides of the tub, and the clothes will be thoroughly cleansed without any rubbing and without frictional contact with any substances which will be calculated to injure them.

15 25 30 35 The attachment may be readily applied to any tub or tank and is simple, durable, and economic and is capable of being operated in a convenient and expeditious manner and without undue exertion on the part of the operator.

40 Having thus described my invention, I claim as new and desire to secure by Letters Patent—

1. In a washing-machine, the combination, 45 with standards, and a grate mounted to rock in the said standards, of a pivotally-mounted

compressing-table above the grate, and locking devices carried by the table and arranged for engagement with the said standards, for the purpose specified.

2. In a washing-machine, the combination, with bifurcated standards, and a grate mounted to rock in the bottom portion of said standards, of a compressing-table mounted above the grate and adjustable to and from the same, and swinging locking devices connected with the compressing-table, adapted to engage with the said standards and hold the compressing-table in its adjusted position, the table being pivotally attached to the locking devices.

3. The combination, with bifurcated standards, a member of each standard being provided with recesses in its inner edge, and a grate mounted to rock in the lower portions of the said standards, of a compressing-table having trunnions, arms pivotally receiving the said trunnions, each arm being provided with a latch-head to enter a recess in said standards, and locking-links pivotally connected with the said arms, also arranged for engagement with said standards, for the purpose specified.

4. In a washing-machine, the combination, with standards, and a grate pivotally mounted in the lower portions of the said standards, the said grate comprising cross-bars and a central tie beam or bar, which extends substantially to the upper surface of the cross-bars, of a compressing-table having an airtight top, a flanged side, a tie-beam and cross-bars extending from the tie-beam, the tie-beam and cross-bars being on the under face of the compressing-table, and locking devices pivotally supporting the compressing-table, and arranged for locking engagement with said standards, for the purpose set forth.

HERMAN G. WEILAGE.
